UNITED STATES PATENT OFFICE.

CHARLES W. BOOTH, OF MILWAUKEE, AND CHARLES GASPAR, OF FOND DU LAC, WISCONSIN.

LIFTING-JACK.

No. 857,225.

Specification of Letters Patent.

Patented June 18, 1907.

Application filed August 25, 1906. Serial No. 331,977.

To all whom it may concern:

Be it known that we, CHARLES W. BOOTH and CHARLES GASPAR, citizens of the United States, and residents of Milwaukee, Milwaukee county, Wisconsin, and Fond du Lac, Fond du Lac county, Wisconsin, respectively, have invented certain new and useful Improvements in Lifting-Jacks, of which the following is a specification.

10 This invention relates to lifting jacks and relates particularly to lifting jacks comprising means for engaging the body portion of the jack with one piece or object; for holding it down, while another piece or object is being raised by the jack.

15 A specific application of our invention is for use in removing the bearing brasses and wedges from journal bearings, an attachment to the body of the jack being engaged with 20 the car wheel for the purpose of holding it down when the jack is applied to raise the journal box.

25 Among the objects of the invention are to provide means for engaging the body portion 25 of the jack with a wheel or other object which admits of a wide range of adjustment, thus adapting the device for use under varying conditions; which will be simple, strong and durable; which may be quickly and conveniently adjusted for engaging the body portion of the jack with a desired object, as a 30 car wheel; and which is so constructed that it may be folded or secured closely against the side of the body portion of the jack, so as not 35 to interfere with the use of the jack in other applications where said engaging means are not required.

40 A jack of our invention consists of the various features, combinations of features and 40 details of construction hereinafter described and claimed.

45 In the accompanying drawings, in which our invention is fully illustrated,—Figure 1 is a side view of a jack comprising our improved holding device, showing a car wheel and journal box, partly in section. Fig. 2 is an enlarged plan section on the line 2—2 of Fig. 1; and Fig. 3 is a partial side view of a lifting jack embodying our invention in a slightly 50 modified form and illustrating the adjustability of the jointed holding arm.

Referring now to the drawings, A designates a car wheel, B the axle, C the journal

box and D, as a whole, a lifting jack, shown as applied for raising the journal box C in 55 order to disengage the wedge c of the journal bearing from the retaining lug c¹ depending from the top of the journal box C to provide for removing the bearing brass c².

All of the foregoing parts are old and well 60 known and may be of any usual or desired construction. As shown, the jack D is what is known to the trade as a "Norton" jack.

Where no means are provided for holding a car wheel down, it is found in practice that, 65 as the journal box C is raised by the jack D for the purpose of removing the bearing brass, the weight of the car, acting on the axle through the journal box at the opposite side of the car, causes the wheel to rise with 70 the journal box so that, when the journal box has been raised a sufficient distance to enable the wedge and bearing brass to be removed, it is necessary to pinch the wheel and axle down by means of a suitable bar, in order to 75 disengage the wedge from the retaining lug. In the type of jack to which our invention relates, means are provided for engaging the body portion of the jack D with the wheel A whereby said wheel will be held down as the 80 journal box C is raised, thus obviating the necessity of pinching down said wheel A and the axle B in the manner heretofore described.

Our improved means for engaging the body portion of the jack D with the wheel A 85 or other object for the purpose of holding it down, consists of a jointed arm, indicated as a whole by E and comprising arm members 1 and 2, of which the member 1 is pivotally connected to the body portion of the jack D 90 and the member 2 is pivotally connected to the free end of the member 2 being designed for engagement directly with the rim of the car wheel A or other object.

In Figs. 1 and 2, the jointed arm E is 95 shown as pivoted to a lug 3 formed integral with a band or collar 4 secured to the upper contracted portion or neck 5 of the body portion of the jack D. As shown, said band or collar 4 is split and is adapted to be clamped 100 in position by means of a clamping bolt 6 which passes through the flanged end 7 of said band or collar.

To relieve the band or collar 4 from the strain due to the action of the holding arm 3 105 in the operation of the jack, we provide a lug

8 thereon which bears against the side of the body portion of the jack D above the point of pivotal attachment of the arm member 1 to the lug 3.

5 The arm members 1 and 2 are adapted to be secured in desired pivotal adjustment, the arm member 1 to the lug 3 and the arm member 2 to the arm member 1 by means of interlocking parts thereon, as shown, by radial teeth 9 formed on the engaging surfaces of said lug 3 and arm members 1 and 2, respectively. Engagement and disengagement of the teeth 9 to secure said arm members 1 and 2 in given pivotal adjustment and to release the same to provide for changing the adjustment thereof, is effected by means of clamping screws 10 and 11, each of which passes through one of the members which they respectively connect and is threaded 20 into the other.

The clamping screws 10 and 11 are of such length that they may be loosened a sufficient distance to permit disengagement of the teeth 9 without removing said screws from 25 the members into which they are threaded, and cotter keys 12 secured in suitable holes formed adjacent to the ends of said clamping screws operate to prevent disengagement of said clamping screws from the members into 30 which they are threaded.

The wide range of adjustability of our improved holding device is illustrated in Fig. 3, in which the holding arm E is shown in a number of different positions. In this figure we 35 have also shown, at 13, said holding arm folded up closely against the side of the body portion of the jack D, in which position it is out of the way and will not interfere with the use of the jack in application where the use 40 of said holding arm is not desired.

Instead of forming the pivot lug 3 on a separate band or collar 4, as shown in Figs. 1 and 2, which construction is resorted to when it is desired to apply our improvements 45 to jacks not embodying the same, we contemplate equally forming said lug integral with the body portion of said lug 3. This modified construction is illustrated in Fig. 3 of the drawings, in which the lug to which said 50 jointed arm E is pivoted is designated by 31.

The manner of using our improved jack will be readily understood by those familiar with the art without a detailed description thereof.

We claim:—

1. The combination with a lifting jack, of a jointed arm pivotally connected to the body portion of the jack, interlocking parts on the body portion of the jack and on the members of said arm adapted for securing said arm to the jack body and the arm members to each other in adjusted position and means for securing said interlocking parts in engagement. 55

2. The combination with a lifting jack, of a jointed arm pivotally connected adjacent to the upper end of the body portion of the jack at a point laterally beyond the side thereof to provide for holding said arm against the body portion of the jack when not in use, interlocking parts on the body portion 60 of the jack and on the members of said arm adapted for securing said arm to the body portion of the jack and the arm members to each other in adjusted pivotal positions and means for securing said interlocking parts in engagement. 70

3. The combination with a lifting jack, of a jointed arm pivotally connected to the body portion of the jack, interlocking parts on the body portion of the jack and on the members 80 of said arm for securing said arm to the body portion of the jack and the arm members to each other in adjusted pivotal positions and means for securing said interlocking parts in engagement, said means comprising clamping screws passing through one connected member and threaded into the other. 85

4. The combination with a lifting jack, of a band or collar secured to the body portion thereof, a jointed arm pivoted to said band 90 or collar, interlocking parts on said band or collar and on the members of said arm adapted for securing said arm to said collar and the arm members to each other in adjusted positions, means for securing said interlocking parts in engagement and a lug on said collar adapted to bear against the side of the body of the jack above the point of pivotal attachment of said jointed arm thereto. 95

In testimony, that we claim the foregoing 100 as our invention, we affix our signatures in presence of two subscribing witnesses this 20th day of August, A. D. 1906.

CHARLES W. BOOTH.
CHARLES GASPAR.
